[57] CLAIM

The ornamental design for a flow generator, as shown.

DESCRIPTION

FIG. 1 is a perspective view of the flow generator of the present invention.

FIG. 2 is a front end view of the flow generator of the present invention.

FIG. 3 is a top view of the flow generator of the present invention.

FIG. 4 is a view of the left side of the flow generator of the present invention.

FIG. 5 is a view of the right side of the flow generator of the present invention.

FIG. 6 is a rear view of the flow generator of the present invention.

FIG. 7 is a bottom view of the flow generator of the present invention.

FIG. 8 is an exploded front perspective view of the flow generator of the present invention with the handle in an extended position.

FIG. 9 is an exploded rear perspective view of the flow generator of the present invention with the handle in an extended position and a rear panel in open position.

FIG. 10 is a left side view of the flow generator of the present invention with the handle in an extended position and the rear panel in an open position; and,

FIG. 11 is a bottom view of FIG. 10.
